UNITED STATES PATENT OFFICE.

WILLIAM A. JOHNSTON, OF CLIFTON, AND ARTHUR W. BROWNE, OF WESTFIELD, NEW YORK, ASSIGNEES TO THE S. S. WHITE DENTAL MANUFACTURING COMPANY, OF PHILADELPHIA, PENNSYLVANIA.

DENTAL PLIERS FOR ADJUSTING TOOLS IN HAND-PIECES.

SPECIFICATION forming part of Letters Patent No. 319,584, dated June 9, 1885.

Application filed April 19, 1884. (No model.)

To all whom it may concern:

Be it known that we, WILLIAM A. JOHNSTON, of the village of Clifton, in the county of Richmond and State of New York, and 5 ARTHUR W. BROWNE, of the village of Westfield, in said county and State, have jointly invented certain new and useful Improvements in Dental Pliers for Adjusting Tools in Hand-Pieces, of which the following is a specification.

The improvements claimed herein relate more particularly to a tool or device for inserting and forcing the operating-tools into and removing them from the tool-holders of 15 what are known as "angle attachments" for use in connection with the hand-pieces of dental engines.

The object of our invention is to provide an improved instrument or device for the purposes mentioned, and designed for use more particularly with tool-holders so organized as to receive and drive operating-tools from either side, and the tools depending for their driving-connection with the socket of the tool-holder upon friction alone. In such tool-holder it is necessary to wedge or force the tool-shanks tightly into the socket of the tool-holder, so as to secure a firm driving-connection, and to attain this end rapidly and with 25 ease to the operator, and further to provide for the easy removal of the operating-tools from the tool-holder, we have devised the improved instrument or device which forms the subject-matter of this present application.

30 The subject-matter claimed is particularly recited at the close of the specification, and some of our improvements so claimed may be used without the others.

In the accompanying drawings we have 40 shown our improvements as organized for operation in connection with an angle attachment of our invention, for which an application was filed January 30, 1884, No. 119,212. Our improvements may, however, be used in 45 connection with other forms of tool-holders and angle attachments, and in any connection in which they may be useful.

We do not claim herein any part of the angle

attachment which we have particularly shown and described in illustrating the operation of 50 our improved implement or device, such being the subject-matter of our aforesaid application filed January 30, 1884. This present application is filed as a division and continuation of said application, in which our improved tool setting and removing implement or device is shown and described, but disclaimed in favor of this present case.

In said drawings, Figure 1 is a view in elevation of the attachment, and Fig. 2 a longitudinal section thereof. Fig. 3 is a sectional view of a pair of forceps or pliers organized for the purpose of inserting and securing the tools in the angle attachments, and of removing them from the tool-holder thereof. Fig. 65 4 is a plan of said forceps, and Figs. 5 and 6 illustrate, respectively, the manner of removing the shank of the bit or tool from the tool-holder of the attachment, and of inserting the shank of the tool in such tool-holder. 70

The angle attachment shown in the accompanying drawings consists, as usual, of a barrel or tube, A, a driving-shaft, B, fitted to turn in said barrel or tube, and carrying the pinion C at its front end, and a head, D, connected 75 with said barrel or tube, and fitted with bearings for a tool-holder, F, having a rigidly-connected gear-wheel, f, meshing with and being driven by the pinion C of the driving-shaft B. The head D is of peculiar construction, and is 80 connected with the barrel or tube A by a peculiarly-constructed shank, d'; but as these peculiarities of construction of the attachment do not form part of the subject-matter claimed herein they need not be more fully described. 85 The tool-holder F is a tubular spindle open at both ends, or has its opening extending through it, and this opening is preferably a double-tapered opening, as shown in Figs. 2, 5, and 6. 90

The bits or tools to be inserted in and driven by the tool-holder F of the attachment are preferably constructed as clearly shown in Figs. 2, 5, and 6—that is to say, with a tapering or wedge shank, g, an enlargement or shoulder, 95 g', and an operating end, g''. The shanks of

the bits or tools are held in the tool-holder F of the attachment, and driven firmly thereby by means of friction, the tapering shanks of the tools being forced into the end of the tool-holder, as clearly shown in Figs. 1 and 2.

In order to provide for the ready insertion and removal of the bits or tools from the tool-holder of the attachment, I have organized a pair of pliers or forceps, or a device having two jaws, as shown in Figs. 3, 4, 5, and 6, one jaw or beak thereof having a punch or plunger, h, rigidly attached thereto, while the opposite jaw or beak is slotted, as at h', the slot terminating in an enlarged recess, h'', which recess is large enough to permit the passage through it of the shoulder g' and shank of the tool, while the slot h' permits the passage between it of the reduced portion of the tool in front of its shoulder g', while it is not of sufficient width to permit of the passage through it of said enlargement g' and the shank of the tool.

In order to insert and lock a bit or tool in the tool-holder of the attachment the head of the attachment is passed between the outer ends of the forceps with the end of the beak or jaw carrying the plunger h bearing upon the upper end of said head, while the tool is inserted in the tool-holder and passed with its reduced portion in front of its shoulder g' into the slot in the opposite jaw or beak of the forceps, as shown in Fig. 6. By forcing the handles of the forceps together it will now be obvious that the tapered or wedge-shaped shank of the tool will be forced firmly into the socket of the tool-holder F, and will be securely locked therein, so that when driven in operation firm connection with the tool is had.

In order to remove the tool from the tool-holder F the head of the attachment is passed between the jaws to a greater extent than before, and sufficiently far to permit the entrance

of the plunger h into the upper end of the holder F, and to bring the enlargement g' of the tool in the enlarged recess h'' of the opposite jaw. It will be obvious now that in closing the handles of the forceps the plunger or punch h will force the bit or tool out of the tool-holder, its escape being permitted through the recess h'' of the opposite jaw, which jaw affords a bearing for the lower end of the tool-holder. It will thus be seen that the operating-tools of the attachment may be readily inserted in and are removed from the tool-holder, as desired, while in operation a firm driving-connection is had.

As we have stated before, we do not claim herein the particular improvements in tool-carriers or angle attachments and in operating-tools therefor shown or described herein, as they constitute the subject-matter of our aforesaid application of January 30, 1884; but

What we do claim herein is—

1. An implement having two jaws or beaks, one jaw of which is provided with a plunger or punch, and the other jaw of which is provided with a slot having an enlargement or recess in a portion of its length, substantially as described, whereby the insertion in and removal of tools from a tool-holder may be facilitated, substantially as described.

2. The implement consisting of two jaws, one of which is provided with a slot having an enlargement or recess in a portion of its length, substantially as described.

In testimony whereof we have hereunto subscribed our names.

WILLIAM A. JOHNSTON.
ARTHUR W. BROWNE.
